UNITED STATES PATENT OFFICE.

FRANK A. RAUNER, OF ELLENVILLE, NEW YORK.

PILE FABRIC.

1,057,274.

Specification of Letters Patent. Patented Mar. 25, 1913.

Application filed February 8, 1912. Serial No. 676,228.

To all whom it may concern:

Be it known that I, FRANK A. RAUNER, a citizen of the United States, residing at Ellenville, in the county of Ulster, State of New York, have invented certain new and useful Improvements in Pile Fabrics; and I do hereby declare the following to be a full, clear, and exact description of the invention, such as will enable others skilled in the art to which it appertains to make and use the same.

This invention relates to pile fabrics and particularly to rag carpets.

In the ordinary weaving of rag carpets the warp threads are formed of hemp or other strong compact strands, while the weft of the carpet is formed of strips of rag interwoven with the warp thread in such manner that certain portions of the latter are directly exposed to wear in the completed carpet with the result that said warp threads become severed when the carpet is subjected to a relatively small amount of usage and the life of the carpet terminated.

It is therefore the object of the invention to produce a rag carpet through the instrumentality of a novel weave whereby the warp threads are completely protected against wear during the use of the carpet.

A further object of the invention resides in the provision of a rag carpet having greater weight and superior strength and therefore superior wearing qualities to those carpets now in use of a similar type.

With the above and other objects in view, the invention consists in the details of construction and in the arrangement and combination of parts to be hereinafter more fully described and particularly pointed out in the appended claim.

In describing the invention in detail, reference will be had to the accompanying drawings wherein like characters of reference denote corresponding parts in the several views, and in which—

Figure 1 is a plan view of a section of rag carpet constructed in accordance with the invention and having the warps, wefts and pile wefts thereof spread apart to more clearly disclose the manner of weaving, Fig. 2, a section on the line 2—2 of Fig. 1, Fig. 3, an enlarged section in the direction of the warps through a fabric constructed in accordance with the invention, and Fig. 4, an

enlarged section taken in the direction of the wefts through a fabric constructed in accordance with the invention.

Referring to the drawings the warp of the carpet is indicated at 10 and each of same is shown as comprising a relatively compact strand of strong material such as hemp.

The weft of the carpet is indicated at 11 and is shown as comprising strips of rags suitably connected together and extending transversely of the warps 10, said wefts 11 being interwoven with the warps 10 in the usual and well known manner and forming in connection with the latter the body or base of the carpet. The warps 10 when thus associated with the wefts 11 are exposed directly to wear as will be apparent and in order to obviate this objection there is employed a pile weft 12 also formed of suitably connected strips of rag and interwoven with the warps 10 between adjacent wefts 11 so as to be clamped and held in place by the latter. In weaving the wefts 12 through the warps 10 said wefts are projected beyond the outer face of the carpet so as to form loops or tufts 13. These loops or tufts being drawn up by hand by pulling each one separately with the fingers, a rod of desired size is then thrust through each loop to hold it in place and so on across the whole width and after the beater is jammed up, the rod is withdrawn. As the inner ends of these loops or tufts 13 are tightly bound together with the warps 10 and wefts 11 the outermost portion of said loops will occupy a spread relation to the inner ends thereof so that said loops will cover the entire outer face of the body of the carpets and protect the warps 10 from direct wear.

What is claimed is:

In a rag carpet fabric, the combination with warp threads and rag wefts, of pile rag wefts each extending continuously from side to side of the fabric beneath alternate warps and between alternate rag wefts, the pile being drawn up in the form of loops and broadened above the rag wefts to form a substantially continuous surface.

In testimony whereof I affix my signature in presence of two witnesses.

FRANK A. RAUNER.
